CYLINDER REAMER

Joseph L. Campbell, Maryville, Tenn.

Application January 18, 1937, Serial No. 121,198

12 Claims. (Cl. 77—2)

This invention relates to an improvement in cylinder reamers of the type commonly used for reaming out the cylinder bores of an engine block.

In the operation of an internal combustion engine, the walls of the cylinder become worn to some extent in the region of travel of the pistons, but this wear does not extend entirely to the ends of the cylinders because the upper piston rings do not travel that far, which leaves an internal ridge in each cylinder, which must be removed or reamed out in dressing or reboring the cylinder.

Reamers have been devised heretofore for doing this work, but they have not been satisfactory because they were inefficient, complicated in construction, expensive to manufacture and otherwise objectionable. The cost of these reamers has been so great as to almost prohibit the purchase thereof by the owners of small garages.

The object of this invention is to simplify the construction of a reamer of this character so as to enable it to be manufactured and sold at comparatively small cost within the reach of every one having use therefor, while at the same time increasing the efficiency and operation of the reamer to enable it to perform its work effectively and satisfactorily. Provision is made for adjusting the reamer to fit cylinders of different sizes so that one reamer may be used and adjusted to the sizes of the different cylinders to be reamed out or rebored. This adjustment may be effected very simply by an adjustment of guide rollers provided for guiding the movement of the reamer in the cylinder and also, if desired, an adjustment of the cutter.

In carrying out this object, a reamer stock is provided with a plurality of guide rolls on different sides thereof, at least one set of which is made adjustable, so that the guide rollers may be adjusted to fit different sized cylinders, and the cutter is also adjustably connected with the reamer stock and preferably disposed, so as to be on the same side thereof, as certain of the rollers, while other rollers are on the opposite side of the reamer stock from the cutter.

A bracket is adjustably connected with the upper portion of the stock and carries one or more rollers for varying and adjusting the position of the reamer with respect to the cylinder.

A preferred embodiment of this invention is set forth in the accompanying drawings, in which:

Fig. 1 is a vertical sectional view through an engine cylinder showing the improved reamer in side elevation therein;

Fig. 2 is a horizontal sectional view therethrough on the line 2—2 of Fig. 1;

Fig. 3 is a top plan view of the reamer in place in the cylinder;

Fig. 4 is a horizontal sectional view therethrough on the line 4—4 of Fig. 1;

Fig. 5 is a similar view on the line 5—5 of Fig. 1;

Fig. 6 is a detail transverse sectional view through the supporting bracket, on the line 6—6, of Fig. 3;

Fig. 7 is a detail edge view of the upper set of guide rolls; and

Fig. 8 is a side elevation, partly in section, of one set of guide rollers and the mounting thereof.

An engine cylinder block is designated generally by the numeral 1, and has the usual engine cylinder 2 therein, in which a reciprocating piston normally operates. The piston rings usually cause wear of the walls of the cylinder 2, during normal operation of the engine, but because the uppermost ring does not reciprocate to the full end of the cylinder, this wear results in the formation of a slight ridge in the cylinder which is designated generally by the numeral 3, and in reboring the cylinder for fitting new pistons or rings to the engine, it is desirable that this ridge 3 be removed by means of a reamer.

My improved reamer comprises a reamer stock designated generally by the numeral 4, which is shown in Fig. 1, as having portions 5 and 6, slightly offset in different directions to receive and mount the respective rollers which guide the turning movement of the reamer in the cylinder.

The stock 4 has a screw stud 7, fixed therein in an end of the offset portion 5, as shown in Fig. 1, which stud projects lengthwise therefrom and receives a bracket 8, which is adjusted relative to the stud by means of adjusting nuts 9 threaded thereon on opposite sides of the bracket 8. The bracket 8 has downturned arms 10, which receive and mount a wheel 11, shaped to revolve on the upper end of the cylinder block around the engine cylinder and to guide the turning movement of the reamer therein. The position of the reamer with respect to the end of the cylinder may be varied by adjusting the nuts 9.

As shown in Figs. 1 and 3, the bracket 8 surrounds the stock 4 for adjustment lengthwise thereof and on the opposite side of the stock 50 from the stud 7, the bracket 8 is slotted as at 12 to receive an adjusting bolt 13, of a mounting 14 which carries a wheel 15 therein riding on the end of the engine block 1. The mounting 14 may be adjusted back and forth relative to the cyl- 55

inder as desired and is guided by downturned portions 16 on the edges of the bracket 8, as shown particularly in Fig. 6. This provides a free rotary motion of the reamer upon wheels at 5 opposite sides of the cylinder, one of which wheels may be adjusted toward or from the cylinder according to the size thereof and the location of valves or associate parts of the engine.

The reamer is provided with a cutter 17 at the 10 upper end of the offset portion 5 of the stock, which cutter may have straight or tapered edges according to the cylinder to be operated upon. The cutter 17 is inserted into an opening 18 in the reamer stock against an adjusting screw 19 threaded into the opposite edge thereof and is 15 locked in place by means of a set screw 20, as shown in Fig. 4. This enables the cutter 17 to be removed or replaced as desired or adjusted to fit different cylinders.

20 A frame 21 is inserted transversely in a notch 22 in an edge of the offset portion 5 of the reamer stock, which frame is secured in place by a stud bolt or screw 23, which is inserted through the frame 21 into the reamer stock. Rollers 24 are 25 journaled in opposite ends of the frame 21 and rotate in the cylinder in contact with the walls thereof just beneath the cutter 17, so as to brace the reamer at or adjacent the point of cutting.

Immediately below the rollers 24 on the same 30 side of the cylinder as said rollers is a frame 25 secured to the offset portion 5 by a locking screw 26. The frame 25 has offset arms 27 arranged in pairs and in which arms are journaled four rollers 28 arranged as shown in Fig. 2, to engage 35 a side of the cylinder and to guide the lower end of the reamer in the rotary motion thereof.

On the opposite side of the reamer stock 4 from the sets of rollers 24 and 28, is another set of four rollers 29, journaled in offset arms 30 of a frame 31. The frame 31 is mounted loosely on a bolt 32, one end of which is threaded into the offset portion 5 of the reamer stock with a coil spring 33 interposed between a nut 34 on the bolt and one side of the frame 31, so as to permit 45 yielding motion of the rollers against the side of the cylinder.

On the opposite side of the frame 31 is a wing nut 35 threaded on the bolt 32 for adjusting the frame and the rollers outwardly toward the cylinder wall, and a cupped spring 36 is interposed between the wing nut 35 and the frame 31 to provide a resilient pressure against the frame. The bolt 32 may be removed and replaced with a long bolt where necessary in adapting the reamer to a larger sized cylinder. By turning the nut 35, the rollers 29 may be adjusted out or back, so as to accommodate for cylinders of different sizes. The frame 31 has a depending lug 37 thereon to which is fixed a pin 38 slidably extending into an opening 39 in the reamer stock 60 for stabilizing the position of the rollers 29 in their different adjusted positions.

This reamer is supported by the wheels 11 and 15 for operation in the cylinder, substantially in 65 the position shown in Fig. 1. In this position the rollers 24, 28 and 29 bear against the sides of the cylinder as shown in Figs. 2 to 5, so as to guide the rotary motion of the reamer in co-operation with the wheels. In this position also, 70 the cutter 17 bears against the ridge 3 to be cut away.

Rotary motion is imparted to the reamer in the usual way by the use of a wrench or tool connected with the upper end of the reamer stock, 75 which rotary motion causes the cutter to ream

away the ridge 3, the cutter being adjusted as the work progresses and any adjustment lengthwise of the cylinder that may be necessary being accomplished by adjusting the nuts 9 on the studs 7. The only adjustment necessary in order 5 to accommodate the reamer to different sizes is the adjustment of the wing nut 35 to move the rollers 29 out or back, in order to provide a proper operating fit of the rollers in the desired cylinder. Where there is a great difference between the 10 small and large sizes of adjustment, the wheel 15 may be adjusted as well as the adjustment of the wing nut, and if desired an extra length bolt 32 may be substituted for the shorter one, but ordinarily the one adjustment of the wing 15 nut will be all that is required for most cylinders from the smallest to the largest in normal use.

This reamer provides a secure mounting in the cylinder, an effective operation in removal of the ridge thereof with simple adjustment to accommodate for different sized cylinders, and the reamer may be constructed at small cost, so as to be made available for purchase by garage owners of small means and at a reasonable cost.

I claim:

1. A cylinder reamer comprising a reamer stock, a cutter carried thereby, said reamer stock being elongated in bar shape and having a plurality of longitudinally spaced portions laterally offset in different directions from the center axis thereof approximately in zigzag shape, and a plurality of guide rollers attached respectively to said offset portions and carried thereby for guiding the turning movement of the reamer in a cylinder. 30

2. A cylinder reamer comprising a reamer stock, a cutter carried thereby, said reamer stock being elongated in bar shape and having a plurality of longitudinally spaced portions laterally offset in different directions from the center axis thereof approximately in zigzag shape, a plurality of guide rollers attached respectively to said offset portions and carried thereby for guiding the turning movement of the reamer in a cylinder, and means for adjusting one or more of said rollers radially relative to the reamer stock. 35

3. A cylinder reamer comprising a reamer stock, a cutter carried thereby, a screw extending laterally from the reamer stock and having a head thereon, a frame mounted on the screw and carrying a plurality of rollers for guiding the turning movement of the reamer in a cylinder, a spring interposed between the frame and head, a nut threaded onto the screw on the opposite side of the frame from the head for adjusting the position of the frame relative to 50 the screw, and resilient means interposed between said nut and the frame. 55

4. A cylinder reamer comprising a reamer stock, a cutter carried thereby, a plurality of roller supports each carrying one or more rollers and 60 mounted at different sides of the reamer stock for guiding the turning movement of the reamer in a cylinder, at least one of said roller supports being adjustable radially relative to the reamer stock, said adjustable support having an offset 65 lug thereon and a guide pin connected with said lug and with the reamer stock for holding the adjustable support in proper relation thereto.

5. A cylinder reamer comprising a reamer stock elongated in bar shape and having longitudinally 70 spaced portions of the body portion thereof wholly offset laterally in different directions, a cutter carried by the reamer stock, roller frames each having one or more rollers and secured respectively to the laterally offset portions of the 75

reamer stock for guiding the turning movement of the reamer in a cylinder, at least one of said roller frames being on the same side of the reamer stock as the cutter and another of 5 said frame being on the opposite side therefrom, and means for adjusting the last-mentioned frame radially relative to the reamer stock.

6. A cylinder reamer comprising a reamer stock having an operating shank, a cutter carried by 10 the reamer stock, said reamer stock having a laterally offset portion at one side of the operating shank, an adjusting screw secured to said offset portion, a bracket adjustably attached to said screw and having means thereon for supporting 15 the reamer.

7. A cylinder reamer comprising a reamer stock having a shank with a laterally offset portion, a cutter carried by the reamer stock, a screw secured to the offset portion and extending 20 lengthwise of the reamer stock approximately parallel with the shank, and a bracket adjustably connected with the screw and having a roller on one side of the reamer for supporting the same in a cylinder.

8. A cylinder reamer comprising a reamer stock having a shank with a laterally offset shoulder portion, a cutter carried by the reamer stock, a screw secured to the offset shoulder portion and extending lengthwise of the reamer stock be- 25 side the shank and approximately parallel therewith, a bracket adjustably connected with the screw and having a roller on one side of the reamer for supporting the same in a cylinder, a roller mounting on the opposite side of the 30 reamer from the bracket and slidably connected therewith, and means for securing the mounting to the bracket in different adjusted positions thereto.

9. A cylinder reamer comprising an elongated 40 bar-shaped reamer stock having a portion intermediate the ends thereof bodily offset from the major portion of said reamer stock providing longitudinally spaced recesses one within said offset portion and another spaced therefrom, roller supports mounted in said recesses carrying 45 rollers for guiding the turning movement of the reamer, means for adjusting one of said supports radially relative to the reamer stock, a cutter carried by the reamer stock, and means 50 for supporting said reamer stock for turning movement in a cylinder.

10. A cylinder reamer comprising an elongated bar-shaped reamer stock having a shank at one end and a portion at the opposite end substan-

tially in alignment with the shank with the intermediate portion connecting said shank and last-mentioned end bodily offset out of longitudinal alignment with the shank and said end providing a recess on the axis of the reamer stock, 5 a roller support mounted in said recess and adjustable radially of the reamer stock, a roller support secured to the end on the opposite side from the recess, a cutter carried by the reamer stock, and means for supporting said reamer stock for 10 turning movement in a cylinder.

11. A cylinder comprising an elongated bar- 15 shape reamer stock having a shank at one end and a portion at the opposite end substantially in alignment with the shank with the intermediate portion connecting said shank and last-mentioned end bodily offset out of longitudinal alignment with the shank and said end providing a recess on the axis of the reamer stock, a screw member secured to said offset position and ex- 20 tending radially in the recess, a roller support mounted on the screw member, a nut threaded on the screw member for adjusting said roller support radially, a roller support secured to the end of the reamer stock on the opposite side from 25 the recess, rollers carried by said roller supports, a cutter carried by the reamer stock, and means for supporting the reamer stock for turning movement in a cylinder.

12. A cylinder reamer comprising an elongated 30 bar-shaped reamer stock having a shank at one end and a portion at the opposite end substantially in alignment with the shank with the intermediate portion connecting said shank and last-mentioned end bodily offset out of longitudinal alignment with the shank and said end providing a recess on the axis of the reamer stock, a screw member secured to said offset portion and extending in the recess, a roller support mounted on the screw member, a nut threaded 35 on the screw member for adjusting said roller support radially, a roller support secured to the end of the reamer stock on the opposite side from the recess, rollers carried by said roller supports, a cutter carried by the reamer stock, a screw 40 secured to the offset portion at one side of the shank and extending approximately parallel therewith, a bracket mounted on said screw for axial adjustment lengthwise thereof, and guide rollers carried by the said bracket for engaging 45 an end portion of a cylinder structure to support the reamer therein.

JOSEPH L. CAMPBELL.
